UNITED STATES PATENT OFFICE

EARL DWIGHT COVELL, OF PHILADELPHIA, PENNSYLVANIA, ASSIGNOR TO THE COVELL CORPORATION, OF WILMINGTON, DELAWARE, A CORPORATION OF DELAWARE

WALL CONSTRUCTION

Application filed January 24, 1929. Serial No. 334,724.

This invention relates to the construction of walls, and is more particularly concerned with erection of walls from standardized block units.

5 The purpose of my invention is to enable construction of walls of any required depth or thickness more rapidly and expeditiously than possible under existent methods, and with great saving in the number of building 10 units required and corresponding economy in the cost of laying or erection.

How the foregoing and other important advantages can be readily attained in practice without sacrifice either of strength, rigidity or stability in the walls, will be manifest from the detailed description which follows.

In the drawings, Fig. I shows a side elevation of a triple thickness building wall embodying my invention in one form.

Fig. II is a plan sectional view of the wall taken as indicated by the arrows II-II in Fig. I.

Figs. III and IV are anterior and posterior 25 perspective views showing the manner in which the frontal or "barrier" thickness of the wall of Figs. I and II is constructed from special facing units.

Fig. V is a perspective view illustrating 30 the novel arrangement of ordinary building units in the double backing thickness of the wall of Figs. I and II.

Figs. VI, VII and VIII are illustrations 35 respectively similar to Figs. I, II and V showing a modified arrangement of the units comprising the wall.

Figs. IX and X are plan sectional views like Figs. II and VII showing still other modifications.

40 Referring first to Figs. I-V of these illustrations, the form of wall there shown is of triple thickness, that is to say: it embodies a single frontal thickness 12—in this instance constructed from special molded block units 45 13 of the type shown and described in U. S. Patent #1,662,300 granted to me under date of March 13, 1928; and a double backing thickness 14 constructed from ordinary brick units 15 or the like. The special units 13 are 50 laid in the usual overlapping relation, and

from Figs. III and IV it will be observed that their configuration is such as to define a continuous flush face on the outside, and a system of continuously communicating horizontal and vertical intervening intervals 16, 55 17 open at the rear. In building the wall, I first erect the frontal thickness 12—laying the units 13 dry in interlapping relation as aforesaid and as clearly set forth in Figs. III and IV. I then proceed with the erection 60 of the double backing thickness 14 from the units 15, laying them in pairs side by side longitudinally of the wall with contiguous pairs spaced end for end in one horizontal row for capacity to bridgely support correspondingly spaced units 15 of the superjacent horizontal row laid crosswise—all as shown in Figs. II and V. Incidental to the last described procedure, a narrow vertical interval 18 is left between the outer and inner 65 thicknesses 12, 14 of the wall, as well as a narrow interval 19 in every instance between the longitudinally laid pairs of the units. The wall is finally bonded by introducing 70 from the rear cementitious bonding material M into the transverse spacial intervals 16, 17 and 20, 21 occasioned as a consequence of arranging the units 13, 15 in the manner explained. This may be readily accomplished 75 with the aid of any suitable type of cement "gun" or other device from which the cementitious material mortar or other suitable joint fillers is projected with appropriate velocity under pressure or otherwise. Cementitious material so introduced will readily find its way through the several passages 19 and the intervals 18 into the interspaces 16, 17 between the units 13 of the outer wall thickness, thereby tying the latter units and the units 80 15 of the backing thickness 14 continuously 85 and effectively together into a rigid whole.

In the embodiment shown in Figs. VI, VII and VIII, the units 15a of the inner wall thickness 14a are arranged somewhat differently. Here it will be noted that the units 15a are laid longitudinally of the wall in all the horizontal rows, the modified arrangement permitting greater end for end spacing than in the first described embodiment with resultant greater economization in the num- 90 95

ber of block units 15a required. The modification has the further advantage in that it enables building of walls with a single backing thickness as can be readily visualized by considering the rear thickness in Fig. VII removed.

If desired, ordinary facing brick units may obviously be employed for the outer thickness 12 or 12a of the wall in lieu of the special 10 molded units 13, 13a in either the embodiments of Figs. I-V or Figs. VI-VIII; but in such case, mortar would of course have to be placed between said ordinary units incidental to laying. The procedure followed as 15 regards laying of the backing thickness 14 of the wall and final bonding of the units 15 or 15a would however be exactly as already explained, with the frontal thickness 12a acting (like the frontal thicknesses of the previous 20 forms) after the manner of a barrier to restrain the bonding material.

In instances where a facing thickness is not required or desired, or where merely a rough wall is wanted to serve as a base for 25 stucco or plaster, I may erect, as shown in Fig. IX, a temporary vertical surface 12b—of lumber, building paper or sheet metal—to constitute a barrier for restraint of the cementitious bonding material as it is introduced into the transverse interstices 21b 30 between the units 15b from the opposite side of the wall.

My invention may also be adapted to the construction of a thickness or shell of masonry 35 about frame buildings after the manner illustrated in Fig. X where the letter U designates the upright timbers, and S the siding of a building, the units 15c being laid after the manner of Fig. VIII contiguous to the 40 siding and the cementitious bonding material introduced into the interstices 21c of the wall from the opposite side as in all the other instances. An efficient base is thus provided for application of the stucco or plaster conveniently indicated at 22 in the illustration.

From the foregoing it will be seen that through my improved method, walls of any thickness may be easily erected with a minimum number of block units and therefore at a considerable saving in labor costs of laying over older methods without sacrifice either of strength, rigidity or stability, the block units being so arranged in all instances 55 as to constitute a mould which is afterward filled in with the cementitious bonding agent.

It is of course to be understood that the arrangement of the units is obviously susceptible to considerable diversification, and I do not, therefore, wish to be limited to the precise groupings herein exemplified.

Having thus described my invention, I claim:

1. The new art of wall construction which 55 consists in erecting a vertical barrier surface,

laying building blocks row upon row contiguous to the barrier surface with the blocks of one row laid so as to afford relatively large open spaces providing bridging support for the blocks of a superjacent row and of differing cubic capacity at paralleling edges only, and bonding such structure with suitable material applied under appropriate velocity, by pressure or otherwise, into all the open spaces, occasioned by arranging the blocks as aforesaid, from the opposite side of the wall.

2. A wall constructed from block units laid in horizontal rows with the units in one row spaced apart to afford bridging support for the units of the superjacent row at the edges only, and cementitious bonding material filling the transverse spacial intervals of large cubic capacity occasioned in the wall by arrangement of units as aforesaid.

3. A double wall constructed from block units laid in horizontal rows with the units of one row placed longitudinally side by side in pairs and spaced apart end for end from neighboring pairs to afford bridging support for correspondingly spaced pairs of the units of a superjacent row at the ends only, and cementitious bonding material filling the transverse spacial intervals of large cubic capacity occasioned in the wall by arranging the units as aforesaid.

4. A double wall constructed from counterpart block units laid in horizontal rows with the units of one row placed longitudinally side by side in pairs and spaced apart end for end from neighboring pairs to afford bridging support for correspondingly spaced units of a superjacent row at paralleling edges only, and cementitious bonding material filling the transverse spacial intervals of differing cubic capacity occasioned in the wall by arranging the units as aforesaid.

5. A wall constructed with a continuous frontal thickness formed from block units laid overlappingly and a backing thickness constructed from block units laid in horizontal rows contiguous to the frontal wall thickness with the units of one row spaced apart to afford bridging support for the units of a superjacent row at paralleling edges only, and cementitious bonding material filling all the transverse and intervening spacial intervals occasioned in the wall by arranging the units as aforesaid.

6. A wall constructed with a frontal thickness formed from special units laid overlappingly and jointly providing a continuous anterior face and continuously communicating system of horizontal and vertical intervening intervals between units at the rear, and a backing thickness constructed from ordinary block units laid in horizontal rows contiguous to the frontal thickness aforesaid with the units of one row spaced apart to afford bridging support for correspondingly 130

spaced units of a superjacent row at the ends only, and cementitious bonding material filling all the spacial intervals between the units of both the frontal and backing thicknesses of the wall.

In testimony whereof, I have hereunto signed my name in Philadelphia, Pennsylvania, this 21st day of January, 1929.

EARL DWIGHT COVELL.
